UNITED STATES PATENT OFFICE

FRANK S. BARKS, OF ST. LOUIS, MISSOURI

LUBRICATOR

Application filed September 17, 1930. Serial No. 482,439.

This invention relates to lubricators, and with regard to certain more specific features to an improved lubricating system.

Among the several objects of the invention may be noted the provision of a lubricating system for supplying a plurality of bearings wherein both the amount and character of the lubricating material delivered to individual or groups of bearings may be permanently changed and/or varied; the provision of a device of the class described including means for temporarily changing the rate of delivery of lubricant to all of the bearings in the system; the provision of a device of the class described wherein any given bearing or group of bearings may be temporarily supplied with a greater amount of lubricant; the provision of a device of the class described in which is normally effected a centralized timing of delivery of lubricant to all bearings; the provision of means of the class described including means for changing said timing; and the provision of a device of the class described which is flexible both in application and in operation, which comprises a minimum number of parts, being simple both in operation and construction. Other objects will be in part obvious and in part pointed out hereinafter.

The invention accordingly comprises the elements and combinations of elements, features of construction, and arrangements of parts which will be indicated in the following claims.

In the accompanying drawings, in which is illustrated one of various possible embodiments of the invention,

Fig. 1 is a plan view of an improved pump used in the system, portions being broken away;

Fig. 2 is a side elevation of Fig. 1, portions being broken away;

Fig. 3 is a cross section of certain parts forming a continuation of Fig. 2, said figure being taken on line 3—3 of Fig. 4;

Fig. 4 is a cross section taken substantially on line 4—4 of Fig. 3;

Fig. 5 is a fragmentary cross section taken through the outlet of the pump on line 5—5 of Fig. 1; and,

Fig. 6 is a wiring diagram.

Similar reference characters indicate corresponding parts throughout the several views of the drawings.

Referring now more particularly to Fig. 1, there is illustrated at the letter M an electric driving motor, preferably, though not necessarily of the constant speed type. This motor M is geared to a crank shaft 1 by way of two sets 3 and 5 of reduction gears. The former set 3 of gears is of the non-changeable type; whereas the latter set 5 of gears is of the change-gear type, that is, another set may be substituted therefor of different speed ratio but located on the same centers so as to provide a changeable reduction between the motor and the crank shaft 1. The purpose of this function will appear hereinafter. A countershaft 7 is used between the reduction sets 3 and 5.

The crank shaft 1 carries a double throw crank 9 having crank pins 11 and 13, the former crank pin 11 controlling a main reciprocating pump plunger 15 and the latter pin 13 controlling a connecting rod 17 for oscillating certain valve gears timed with said plunger 15. The crank pin 11 controls reciprocation of the plunger 15 by way of a connecting rod 19, said connecting rod 19 being articulated with the plunger 15 at an articulation 21.

The specific description of the articulation 21 is given in my copending patent application, Serial Number 344,719, filed March 6, 1929. However, the details of this articulation are of less importance here and all that need be noted for a clear description herein is that said articulation 21 permits angular movement between the plunger 15 and connecting rod 19 as the crank pin 11 revolves.

The plunger 15 reciprocates in a pump cylinder 23 which is put into and out of communication with ports 25 and 27 by means of sloping connecting ports 29 and 31 respectively, the center lines of said ports being located in planes at right angles to one another (see Figs. 1 and 5).

As shown, the connecting ports 29 and 31 are bored angularly through an oscillable valve stem 33. This stem 33 extends out-

wardly from a valve casing 35 and is exteriorly provided with an oscillating crank 37.

The valve crank 37 and the driving crank 13 are connected by said connecting rod 17 and a lost motion device 39. The lost motion device 39 comprises a cylinder 41 having shock absorbing means 43 located at the opposite ends thereof. The connecting rod 17 passes slidably into said cylinder 41 and is 10 interiorly provided with a plunger 45 which is adapted to be engaged by the shock absorbing devices 43 as rotation of crank pin 13 takes place. The sequence of events is as follows:

15 As the main crank 11 moves counter-clockwise starting from the Fig. 2 position it inherently effects a slow acceleration and movement at the plunger 15. At this time the cylinder 23 is in communication with the port 20 27, said port 27 being the outlet port for lubricant. Inasmuch as the movement of the plunger 15 at the start of a stroke is relatively slow, the valve 33 may have movement imparted thereto to effect a final setting without 25 deleteriously throttling the then slow flow of lubricant. In order to effect valve movement the crank shaft 13 is arranged so that at this period of slow movement of the plunger 15, said crank 13 has just passed through 30 a period of imparting fast movement to the valve and is approaching a period of imparting slow movement to the valve.

Next, as the movement of the plunger 15 accelerates and comes to a high speed, due to action of the crank pin 11, the valve 33 comes to rest as the crank pin 13 comes to dead center and even after dead center has been passed by said crank pin 13, the valve 33 does not start to move because of the lost motion 35 provided by the device 39. Thus the crank pin 13 starts on its back travel without carrying with it the connecting rod 17 and without imparting motion to the valve stem 33. This condition continues until the crank pin 40 11 approaches its dead center for completing a full pressure stroke and as the plunger 15 slows down and stops, the head 45 of the connecting rod 17 is engaged by the right-hand shock absorber 43. This engagement takes place at or substantially at the period when 45 the crank 13 imparts the highest velocity of movement to the crank 37 and consequently to the valve stem 33. Thus the stem 33 starts from a period of rest with a high acceleration 50 and immediately attains a maximum velocity. This is done at the period of slow movement of the plunger 15. Thus a quick change of port connections is effected at the valve so that upon the back stroke of the plunger 15 maximum port opening is available for drawing in lubricant from the inlet 25.

60 Next, as the crank pin 13 approaches its left-hand dead center and slows down the motion of the valve stem 33, the crank pin 11 gets into its position for transmitting higher

velocity to the plunger 15 on the back stroke of said plunger. Before suction is completed the crank pin 13 has crossed its left-hand dead center and has proceeded to take up the reverse lost motion in the device 39 upon the reverse oscillation of the valve 33, said lost motion being taken up during the high speed return movement of the plunger 15. As the plunger 15 flows up on its suction stroke, the lost motion at the device 39 is all taken up and the valve stem 33 driven with immediate high velocity to the original position for connecting the exhaust port 27 with the pump cylinder 23.

From the above it will be seen that there is provided an advantageous valve mechanism for the reciprocating pump used herein, said mechanism comprising a double throw crank, one throw of which reciprocates the plunger and the other throw of which reciprocates the valve by controlling flow of fluid to and from the reciprocating plunger. The double throw arrangement of the crank is such that the two throws are out of phase enough so with the lost-motion connections each will provide maximum speed of movement when the other is near a minimum. Also, the movement of the valve occurs at high acceleration and speed, whereby a complete resetting of the valve is effected during the period that the plunger rests and is moving only slowly.

As shown in Fig. 1, one end of the inlet passage 25 is closed by means of a plug 47. Upwardly said port 25 communicates with a supply chamber 49 having a follower 51 and inlet means 53 for applying air pressure back of said piston 51. Thus the flow of heavy lubricant into the pump cylinder 23 is facilitated. An outlet relief valve 55 adapted to be manually opened is placed in communication with the outlet port 27 for priming purposes.

In Figs. 4 and 5, at numeral 57 is shown a spring loaded relief valve put into communication with the pump cylinder 23 for the purpose of relieving pressure and permitting escape of lubricant should the valve gear become or be put out of operation. For example, this relief valve would be useful if the lost motion device 39 were to become damaged, so that the valve would operate out of proper time and thus not provide required port opening for effectively handling all of the lubricant during the time available for so doing.

So far, there has been described the advantageous pumping unit used herein. All of its parts are placed upon a base 59 so that it may be carried and placed as a unit in proximity to a bearing which it is to lubricate. The lubricating line 61 leading from the outlet port 27 is put into communication with a bearing. An example of how the machine might be placed would comprise

locating it near a steel mill and leading a trunk and branch lubricating lines from the outlet port 27 to the bearings of said mill. Or, a single bearing might be supplied. 5 Thus it will be seen that it is intended that these units be placed locally about a plant so that local conditions at various bearings may be provided for.

By having one machine at each location, it 10 is possible to vary the character of the lubricant supply to a given bearing as distinguished from that supplied to another. I also vary its amount and vary its period of application. To vary its character, it is only 15 necessary to pour the proper lubricant into the container.

To vary the amount of lubricant the gears 5 may be changed so that the velocity ratio 20 between the motor M and the reciprocating plunger 15 is changed and thus more or fewer strokes can be accomplished during a given period of time and thus delivery of more or less lubricant. The period of application of the grease may be changed in a manner to be 25 set forth hereinafter.

In order to coordinate a plurality, such as 30 four, of the units shown in Figs. 1, 2 and 5, an electric circuit such as shown in Fig. 6 is used. This circuit may be described as follows:

Referring to Fig. 6, there is shown at 35 numeral 63 a main supply circuit. Connected in parallel across the line 63 is a plurality of said motors M driving pumping units 59. The motors M are serially connected with 40 separate magnetic switches 65, so that the motors M and the switches 65 are connected across said line 63. When the switches 65 are closed the respective motors M are energized to drive the pumping unit 59. At 45 numeral 67 is shown a main magnetic switch, the trip coil 69 of which is energized by a shunt 71 connected across swingable contact points 73. The contacts 73 are located in a main or central timing switch 75 which is 50 supplied current by means of a supply circuit 77 connected with the main line 63. It will be understood that the timing switch and the magnetic switches and the like herein described are themselves known and that there 55 is shown and described herein only enough of their elements to make clear the functions of the system herein described.

The contacts 73 are timed to open and close 60 at predetermined intervals by means of a set of cams 79, 81 connected to the same shaft, such shaft being driven by a suitable synchronous or other constant speed motor 105 energized from said circuit 77. It is to be understood that where alternating current is not 65 available a mechanical timing device may be used for driving the cam shaft. For purposes of explanation the cam 79 is shown composed of conducting material and connected so as to continuously maintain the circuit 77

closed. Hence it will be seen that the motor which is energized from said circuit continuously drives the shaft on which the cams 79, 81 are mounted. The cam 81 is shown as

non-conducting. It will thus be seen that the period of time which the contacts 73 remains

closed depends upon the relative positioning of the cams 79, 81 and upon the rate at which they revolve.

The rate at which they revolve is a fixed quantity in a given switch, but the relative angular positions of the cams 79, 81

may be adjusted to suit particular conditions. Thus it will be seen that by means of the timing switch 75, the trip coil 69 of the main

magnetic switch 67 is intermittently energized so as to intermittently close a circuit

83 which circuit 83 in turn energizes the trip coils 85 of said magnetic switches 65 associated with the motors M and pumping unit

59. Energization of the trip coils 85 from the circuit 83 is effected through normally

spring closed contact 87 of push button switches 89. The push button switches 89 are located at local stations preferably near

the units M, 59.

The purpose of the push button stations 90 is to effect manual, temporary starting of the motors M. They include contact bars 91 which are normally spring pressed to main

tain closure of the circuit 83 at the switches

89. By means of manually operable handles 93, the bars 91 may be pushed in so as to close a second set of contacts 95, said contacts 95 being located in a circuit 97 which is fed from the main circuit 63, but the current of which is not adapted to be broken by the magnetic switch 67 regardless of the position of said switch 67.

Thus it will be seen that the trip coils 85 of the magnetic switches 65 are normally fed

current by way of said magnetic switch 67, which switch 67 in turn is under control of the intermittently closed contact 73 of the timer

switch 75. When anyone of the handles 93 is pressed in so as to open the circuit 83 includ-

ing the switch 67, then the circuit 97 is closed so that tripping of the respective switch 65 is effected regardless of the timing required by the timer switch 75. Both circuits 83 and 97 feed the trip coils 85 by way of lines 99 and return current to the main circuit by way of lines 101.

A push button switch 103 is used in connection with the timing switch 75 and magnetic

switch 67 for energizing the trip coils 69 of the magnetic switch 67 independently of the action of the timing switch 75. This is done by shorting out the timer switch as shown

by Fig. 6. The switch 103 is also adapted to be operated from a manually controllable

125 handle 93. From the above the following operation and functions will be clear:

The synchronous motor 105 in the timing switch 75 is continuously driven by the constantly closed circuit 77 which is energized

70

130

from the main circuit 68. Thus, the motor 105 drives the cams 79 and 81. The cams are angularly adjusted on their shaft for providing a suitable period of closure of the contacts 73. Thus the trip coil 69 of the main magnetic switch 67 is intermittently energized so as to intermittently close said magnetic switch 67. It will be understood that the magnetic switch 67 automatically reopens when its coil 69 is de-energized.

Intermittent closure of the switch 67 results in intermittently energizing the circuit 83 and consequently the trip coils 85 of the magnetic switches 65. This results in the motors M being intermittently started and stopped so as to operate the pumps 59 intermittently. It will also be understood that when the trip coils 85 are de-energized that the switches 65 automatically reopen. From the above it will be seen that the whole system is timed to operate intermittently from the timing switches 75. For instance, the motors M may be made to operate once every three minutes for a period of one minute. The one minute period may be varied by adjusting the relative angularity of the cams 79, 81. The three minute interval may be varied by suitable changes in the timing switch 75, such as by varying the gearing between the motor 105 and the shaft of cams 79, 81. This is a change, however, which would seldom be made after installation, the switch 75 being designed for a suitable period of intermittency.

If it be desired to temporarily increase the amount of lubricant pumped by all of the units 59, the manually controllable handle 93 of the central push button station 103 may be pushed so as to energize the trip coil 69 without energy passing through the timing switch 75 whereby the timing switch 75 is temporarily overridden. Thus the trip coils 85 are operated according to the time that the handle 93 is held in and as much lubricant may be pumped as desired. This mode of operation may be desirable, for instance, if the whole series of machine which is being served by the unit 59 experience an overload temporarily. Whenever the emergency is over, the handle 93 may be released so that the effect of the timing switch 75 is again inherent. It is to be understood that the timing switch 75 runs continuously during the time that the handle 93 is pushed in. Thus temporary operation of the system in part or in toto does not interfere with subsequent accurate timing by the switch 75.

Sometimes it is desirable that only one or several, but not all, of the pumping unit 59 be temporarily operated for a longer period than is effected by the timing switch 75. In order to accomplish increased operation of only one unit, it is only necessary to push in the manually operable handle 93 of the respective station switch 89. This causes current to flow in from the circuits 97 and thence

to the respective trip coil 85, thence to operate the switch and the respective unit 59. The handle 93 may be held in as long or as short a period as is desirable to effect a desired result. For instance, a foreman may notice that a particular bearing is growing hot for some reason and, instead of shutting down the whole plant, can, during the working period, temporarily increase the amount of lubricant flowing thereto by operating the respective handle 93. Then, when the plant is idle, the bearing may be repaired so that it may be operated at a later period in conjunction with the system as a whole. Other emergencies which would be provided for by the above function will readily suggest themselves.

To recapitulate, this invention provides for the following:

1. Supplying a plurality of bearings with lubricant from a given system such that each bearing or group of bearings may be supplied with a different lubricant. The reason for this is that separate units supply separate bearings or groups of bearings.

2. The amount of grease pumped at one bearing or group of bearings may be varied after installation from the amount pumped to another bearing or group, because it is possible to insert different gearing in the different units.

3. Normally all bearings are automatically supplied lubricant at timed intervals.

4. All of the bearings may have a supply of lubricant temporarily increased as to amount (see switch 103).

5. Any bearing or group of bearings may have an increased amount of lubricant supplied thereto locally (see switches 89). This feature is also useful in starting the apparatus. For instance, if a particular unit 59 loses its prime, the priming check 55 thereof may be opened while its switch 89 is manually held closed. This lubricant will be discharged from the valve 55 and the operator upon examination will know what kind of lubricant is being used and he will also know the fact that the particular pump is operating properly.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A lubricating system comprising a plurality of pumping units, a driving motor for each unit, a switch for each motor, automatic means for closing said switches to operate the motors according to predetermined

intervals, manual means for closing all of 5 said switches to operate the motors independently of said automatic means and individual manual means for independently closing any one of said switches to operate any motor independently of said automatic means.

2. A lubricating system comprising a plurality of pumping units, individual means for driving said units, individual control means for said individual driving means, automatic means for energizing the control means according to predetermined timing and manual means for energizing any one 15 of said control means to the temporary exclusion of the timing.

3. A lubricating system comprising a plurality of pumping units, individual means for driving said units, individual control 20 means for said individual means, automatic means for energizing the control means according to predetermined timing, manual means for energizing any one of said control means to the temporary exclusion of the timing and means for manually and temporarily 25 causing operation of all of said control means in unison independently of said timing means.

4. A lubricating system comprising a plurality of pumping units, individual means for driving said units, individual control means for said individual means, automatic means for energizing the control means according to predetermined timing, manual 30 means for energizing any one of said control means to the temporary exclusion of the timing, means for manually and temporarily operating all of said control means in unison independently of said timing means and 35 means associated with each pumping unit for changing the amount of lubricant pumped per unit of time.

5. A lubricating system comprising a plurality of pumping units and automatic means 40 for effecting intermittent operation of said units according to a predetermined timing and means for locally, manually controlling the respective units.

6. A lubricating system comprising a plurality of pumping units, automatic means for effecting intermittent operation of said units according to a predetermined timing, means 45 for locally, manually controlling the respective units, manually operable means for temporarily increasing the amount of lubricant pumped independently of the timed means and means for locally changing the amount of lubricant pumped per unit of time.

7. A lubricating system comprising a plurality of pumping units, individual motors 50 for driving said units, individual magnetic switches controlling said motors, a main magnetic switch controlling said individual magnetic switches and a main timing switch controlling 55 said main magnetic switch and man-

ually operable individual switches associated with said individual magnetic switches and also with the timing switch, whereby the timing activity of the timing switch may be temporarily eliminated locally or in toto.

70

8. A lubricating system comprising a plurality of pumping units, individual motors for driving said units, individual magnetic switches controlling said motors, a main magnetic switch controlling said individual magnetic switches, a main timing switch controlling said main magnetic switch and manually operable individual switches associated with said individual magnetic switches, whereby the timing activity of the timing switch may be temporarily eliminated locally.

75

9. A lubricating system comprising a plurality of pumping units, individual motors for driving said units, individual magnetic switches controlling said motors, a main magnetic switch controlling said individual magnetic switches and a main timing switch controlling said main magnetic switch and manually operable individual switches associated with said individual magnetic switches and 80 also with the timing switch, whereby the timing activity of the timing switch may be temporarily eliminated in respect to less than all of the pumping units or to all of them, manual operation of one individual switch for 85 starting one motor not preventing said timing activity in connection with the other motors.

85

In testimony whereof, I have signed my name to this specification this 13th day of 90 September, 1930.

FRANK S. BARKS.
